(57) **CLAIM**

The ornamental design for a dimpled trim for a recessed luminaire, as shown and described.

DESCRIPTION

FIG. 1 is a top perspective view of a dimpled trim for a recessed luminaire, showing our new design;

FIG. 2 is a bottom perspective view thereof;

FIG. 3 is a top plan view thereof;

FIG. 4 is a bottom plan view thereof;

FIG. 5 is a left-side elevation view thereof, the right-side elevation view being the same;

FIG. 6 is a front elevation view thereof; and,

FIG. 7 is a rear elevation view thereof.

The broken lines shown represent unclaimed subject matter and form no part of the claimed design.
